(57) **CLAIM**

The ornamental design for a locker mirror, as shown and described.

DESCRIPTION

FIG. 1 is a perspective view of a locker mirror according to the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the locker mirror shown in FIGS. 1-7 with a storage compartment in an open position;

FIG. 9 is a left side view of the locker mirror shown in FIGS. 1-7 with a storage compartment in an open position; and,

FIG. 10 is a top view of the locker mirror shown in FIGS. 1-7 with a storage compartment in an open position.

All broken lines in the above figures are for illustrative purposes only and form no part of the claimed design.
